TYPEWRITING MACHINE

William F. Helmond, West Hartford, Conn., assignor to Underwood Elliott Fisher Company, New York, N. Y., a corporation of Delaware

Application July 29, 1937, Serial No. 156,328

9 Claims. (Cl. 197—27)

This invention relates to the type-actions of typewriters and more particularly to devices therein for substantially reducing friction and bettering the type impression by obviating the 5 faults such as ghosting or smudging the type characters.

Type-actions as constituted in the well known Underwood standard typewriter are of three parts and include a series of sub-levers or bell-crank 10 having their pivots disposed in a straight line across the machine so that each bell-crank operates in a substantially vertical plane defined by the pivot slot, the bell-crank being operatively connected to a series of key-levers for actuation 15 thereby. The series of type-bars are usually pivotally mounted in a type-bar segment having an arcuate pivot line and in which the various bell-crank slots are disposed radially at varying angles on the segment. Thus, the arms of the type-bars by which same are actuated in typing, project 20 from the segment at increasing angles of inclination from the center of the type-bar series to the outside, so that a number of the outside type-bars have their arms disposed at an acute 25 angle from the vertical. The arms of the bell-crank or sub-levers, each being directed substantially vertically, are bent at their free ends at varying angles into parallelism with the projecting arm of the corresponding type-bars, a 30 pin projecting from the bell-crank arm engaging in a slot of the type-bar arm.

It is at this point of connection, that is between the bell-crank arm and the type-bar arm, that difficulties in operation are had, particularly 35 at the outside connections, these difficulties resulting largely from the differences in operating planes of the bell-crank and the type-bar. Referring particularly to the outside connections, it will be noted that the type-bars thereof, being 40 at an appreciable angle, have their crank-arms operating in a plane tilted substantially from vertical, while the corresponding bell-crank or sub-lever arms swing in a vertical plane and therefore their free ends, during actuation of the type-bars, 45 describe an arc which rises away from the plane of the type-bar arm, particularly during the center part of the stroke. This operative connection of the bell-crank and type-bar produces three distinctive variations in action; the normal distance 50 of the bent end of the bell-crank from the type-bar arm increases during the first part of its advance movement and decreases during the latter part of its advance movement; the bell-crank pin is continuously changing its angular and lateral 55 position relative to the type-bar slot; and the arm of the type-bar skews with reference to the bent end of the bell-crank. As aforesigned, these variations result primarily from the difference in angularity of the planes through 60 which the respective parts of the type-action

swing. As the bell-crank swings back to its initial position all of the foregoing movements are reversed. It may be noted that rigid, truly pivoted bell-crank or sub-levers are important in maintaining the predetermined relationship of the type-bars, particularly of the type themselves. Longer pivot pins or studs have been used between the bell-crank and the type-bars on the outside type-actions with the object of overcoming the difficulties, but an especial trouble in this construction is clinging of the type-bar on the pivot pin or stud so that the bell-crank lifts the tail of its type-bar and so skews or biases the type-bar out of its normal plane. Since the type-bar is formed and mounted so that the type 15 passes centrally through the guide in front of the platen, skewing of the type-bar causes this end of the type-bar to strike one side of the guide and to set up a lateral quivering of the type-bar 20 in the guide as the type strikes the work-sheet on the platen, resulting in an imperfect type impression.

The above inherent faults of a type-action are obviated by providing a novel connection between the bell-crank and the type-bar to accommodate the differences in movement of these members in an even, frictionless manner; the connection including a roller having a compensating sidewise or axial play; a series of such connections for all the type-actions in which the 25 rollers are mounted on studs of varying lengths, 30 the lengths being greatest on the outside type-actions.

A further feature of the invention is a connection that automatically accommodates a varying 35 biasing or skewing relationship between the bell-crank and the type-bar and includes a roller having a circumferential groove with an aperture of much greater width than the thickness of the type-bar, and also such a roller having a side- 40 wise play.

It is an advantage particularly to the outer type-actions to enhance the speed of operation of the typewriter by eliminating the friction in these type-actions to a substantial extent, thereby increasing acceleration in the type-bars, advantageous in effecting the whip action thereof. Such advantages are obtained particularly in the outer type-actions because the side play of the roller readily accommodates itself to the position 45 taken by the type-bar arm so as to actuate same without any skewing of the bell-crank, thus obviating any binding at the bell-crank pivot slot. The roller, having sidewise play, and being rotated during action, readily assumes an aligned 50 position relative to the type-bar arm since the rotation of the roller allows same to move axially on its pin practically without resistance.

In one embodiment of the invention the pivot pins or studs may be of three different lengths, 60

namely: for the five outside bell-cranks on each side the longest pivot pins; for the next three bell-cranks the medium length; for the rest a short stud. The rollers are all of the same dimensions, but are used only on the eight outside bell-cranks on each side. The specific number of keys above stated may be varied to suit the type-action arrangement desired, these numbers being given for example only.

10 The invention also provides certain novel improvements effective during the swing of the type-bars, particularly during the whip action thereof, at the completion of the down stroke of the key-levers. The stop position of the key-levers in down stroke is critical in effecting the whip action, since such limitation determines the point in the type-bar stroke at which the type-bar travels of its own momentum and begins the whip action. Adjustably limiting the key-lever 15 down stroke also serves to co-ordinate the key stroke, type impact, type rebound, and letter-feed release of the carriage during manifolding and while operating at high speeds.

In machines, such as the Underwood, employing type-bars swingable about a fulcrum to a common printing point, there is employed a stop-ring or anvil which the type-bar strikes just before the type strikes the platen, whereby the swinging type-bar is arrested in such manner 20 that the type-end thereof whips to the platen and makes the impression, and then springs away from the platen again to avoid blurring. There is still apt to be some blurring of the impression or some double printing or ghosting due, for instance, to faulty key manipulation.

To overcome these objections and gain other advantages the invention provides a device for arresting the key-lever in its printing stroke before the type strikes the platen. An adjustable 25 stop-device is provided to engage the key-levers near the front ends; the lower the stop is set, the nearer are the type to the platen, and vice versa; the higher the stop device the farther are the type from the platen. After the key-lever is 30 intercepted at the front by the adjustable stop the type-bar is whipped to the platen by momentum, the latter part of the type action being permitted by yieldability of the key-lever. The key-lever is sufficiently springy to permit it to flex 35 so that the type may reach the platen even though the key-lever stop be raised a considerable distance equal to that of a heavy manifolding assembly. The recoil of the type-bar from the platen is impelled by the resilient recovery 40 of the key-lever from its downwardly flexed condition, being also aided in its recoil by its recovery from flexure on the anvil as aforementioned.

The aforesaid adjustable stop embodies means 45 for varying the limit of down-stroke for all the key-levers collectively and it is desired to afford means for varying the limit of stroke of each key-lever individually, and more particularly to vary the distance between the finger-engaged 50 surface of the key on any one key-lever and the part of the lever engaging the stop. In accordance with the invention each key-lever has integrally formed thereon adjacent the key-end a relatively rigid but bendable tongue member 55 which at its free end may engage the stop. Thus, by bending the overhanging member or tongue relative to the key-lever the depth of down stroke for the individual key-lever may be affected. The variation of the individual stroke is effective primarily to co-ordinate the action of the respective 60

type-actions, particularly those at the sides of the machine with the actions at the center of the machine, and, accordingly, the bending of the tongue to the desired setting may be effected at the plant, where adequate facilities are provided, the collective adjustable stop being manipulated by the typist or operator at will for the purposes set forth.

A movable pointer may be mounted over a scale to indicate whether the stop is effective when the type are near the platen and tend to make heavy impressions, or when the type are farther from the platen and so tend to make light impressions on the work-sheet, the pointer being operatively connected to the adjustable stop to be moved thereby.

Certain improvements herein set forth, particularly the adjustable stop for the key-levers, relate to the co-pending application of Jesse A. B. Smith, entitled "Improvements in typewriting machines", Serial No. 109,228, filed November 5, 1936.

Other features and advantages will hereinafter appear.

In the accompanying drawings,

Figure 1 is a partial front elevational view of the type-actions of a typewriting machine, the key-levers and certain other parts thereof being omitted for clarity, and showing also the adjustable stop and indicator for the key-levers.

Figure 2 is a fragmentary sectional view of the type-action shown in Figure 1, taken on a front and rear plane at about the center of the machine, illustrating the type-actions in inactive initial position and showing the letter-feed-escapement mechanism associated therewith, and the adjustable key-lever stop.

Figure 3 is a view similar to Figure 2 but showing the type-action during actuation at the instant of engagement of the key-lever with the stop, the type-bar in full line commencing its whip action by momentum, the dotted-line showing of the type-action representing its position at the instant of impact of the type with the work-sheet, the stop being lowered to afford a heavy type impact as in manifolding.

Figure 4 is a view similar to Figure 3 with the adjustable stop lowered to afford a light type impact as for a single work-sheet.

Figure 5 is a partial enlarged view of the type-action showing the type-bar in full line at the instant of engagement with the segment anvil, the dotted-line showing of the type-bar representing the flexure thereof with the type at impact with a single work-sheet, for example.

Figures 6, 7 and 8 represent comparative elevational views, partly in section, of the operating connection between the bell-cranks or sub-levers, and the type-bar arm at three different stages of action of a typical type-action at a side of the machine, Figure 6 showing the relation of the parts at the start, Figure 7, at an intermediate stage, and, Figure 8 showing the relation at the completion of the stroke.

Figure 9 is a fragmentary elevation of a bell-crank and its stud roller, typical for a group of type-actions at the center of the machine.

Figures 10 and 11 are end elevations of the bell-crank, type-bar arm connections demonstrating the effect of the rollers in accommodating the angular change or skewing of the bell-crank end relative to the type-bar arm, and

Figure 12 is a fragmentary plan view of the letter-feed mechanism, being a view taken on the plane 12-12 of Figure 2.

In the preferred embodiment of the invention illustrated in the drawings, a series of key-levers 14 are provided at their free ends with keys 15 comprising a keyboard of the machine. Finger-pressure of a key 15 causes the key-lever 14 to swing downwardly on its pivot 16 against the pressure of a spring 17 engaging the key-lever 14 adjacent the pivotal end thereof, each spring 17 engaging its key-lever 14 against a cushion stop 18. Intermediate the ends of the key-lever 14 is a laterally-projecting pin 18 engaging in an open slot 19 formed in an arm 20 of a bell-crank or sub-lever 21 so that during depression of the key-lever 14 the bell-crank 21 is caused to swing on a pivot 22. The bell-crank 21 includes an upwardly-extending arm 23 which, at its free end, carries a stud 24 rotatably carrying a roller 25, the roller 25 engaging a slot 26 in a projecting arm or tail 27 of the type-bar 28. A series of type-bars 28 are provided, each being pivotally mounted on a type-bar segment 29 which includes an arcuate pivot pin 30 therein. As each bell-crank 21 is actuated by depression of the associated key-lever 14, the roller 25 on the arm 23, acting in the slot 26, swings the type-bar 28 so that the type characters 31 thereon strike a work-sheet carried on a platen 32, as will be hereinafter described in further detail.

In reference to the general arrangement of the elements in the three-part type-action, as illustrated in Figure 1, it will be observed that the bell-crank pivot 22 is disposed in a straight line extending laterally of the machine, the pivot 22 being retained in a transverse member or frame 33, having a series of vertical slots 34 therein in which the pivot portion of each of the bell-cranks 21 is disposed for guiding in a substantially vertical operating plane. As is usual in three-part type-actions of Underwood machines, the series of type-bars 28 are mounted for guiding movement in the segment 29 which includes a series of radially disposed slots, one for each type-bar 28 to guide same during travel so that its type-end enters a type-guide 35. The radial disposition of the various type-bars from a substantially common center, produces a condition in which the arms or tails 27, extending from the type-bars 28, are disposed at varying angles, increasing in inclination from the center type-actions, so that the extreme outer type-actions have the arms 27 at an appreciable angle from the vertical. The arms 23 of the bell-cranks 21 have their ends bent into spaced parallelism with the projecting arms 27 and, in that the bell-cranks 21 operate in a vertical plane, their free ends, carrying the studs 24 and the rollers 25, describe an arc which deviates from the plane of travel of the arms 27.

This deviation of travel is shown graphically in several stages of action in Figures 6, 7 and 8, Figure 6 illustrating substantially the relation of the parts at the start of operation at which stage the bell-crank arm 23 is close to the type-bar arm 27; Figure 7 showing the relation of the parts intermediate the stroke at which instant the bell-crank arm 23 has moved laterally away from the type-bar arm 27; and Figure 8 showing the relation of the parts at the completion of the stroke at which instant the bell-crank arm 23 has again moved toward the type-bar arm 27. From this it will be readily seen that the roller 25, having sidewise play on the stud 24, will readily assume the position to or from the bell-crank arm 23 as defined by the type-bar arm

The roller 25 having its periphery in rolling contact with the slot 26 during action, is rotated on its stud 24 thereby conduced toward a free axial travel of the roller 25 on the stud 24 because of the constantly changing bearing, which also has the advantage of minimizing wear, since the effect of the roller 25 is distributed over a substantial length of the stud 24.

With further reference to the action of the roller 25 it will also be observed, by reference to Figures 10 and 11, that the end of the bell-crank arm 23 changes its position angularly in relation to the type-bar arm 27 in that the arm 27 moves in a straight path, while the end of arm 23 moves in an arcuate path, as viewed from a point beyond the end of the arm 23. The roller 25 has its periphery formed in a groove diverging at each side in a flange 25a. The root diameter of the roller at the bottom of the groove is such as to permit free rolling in the slot 26 without undue looseness in reversing the action so that the roller may readily roll on one edge of the slot 26 and be free of the opposite edge of the slot. The flanges 25a keep the arm 27 in the groove of roller 25 during lateral movement and, to accommodate varying angular position of the parts as shown in Figures 10 and 11, the flanges 25a are spaced from each other a distance adequate to permit such angular change. The stud 24 may be upset or otherwise formed to provide a collar 24a to retain the roller 25 on the stud 24.

In view of the varying angles of inclination of the various type-bars 28, as shown in Figure 1, the deviation in the path of travel of the type-bar arms 27 and the bell-crank arms 23, increases toward the outer type-actions. From this it will be seen that the studs 24 carrying the rollers 25 may be varied in length to suit each type-action. For practical purposes, however, to effect economies in manufacture, the studs for all of the type-actions may be of three different lengths, namely: for the five type-actions of each side of the machine, studs of maximum length; for the next three type-actions the studs 24 may be of a medium length; and for the remainder of the type-actions at the center of the machine, a short stud will be adequate. In action, the immediate center type-actions produce practically no lateral movement of the parts relative to each other and, therefore, the studs 24 thereof may afford only free rotation of the rollers 25; or, if desired, the rollers 25 may be rigidly affixed to the arms 23, as shown in Figure 9.

The invention includes the provision of means for adjustably limiting the downward stroke of the key-levers so that the point in the stroke of the type-bar at which same starts to travel of its own momentum may be varied to the desired distance from the platen or work-sheet. By such adjustment the operator may conveniently regulate all the type-actions collectively for a relatively light or heavy type impact to suit the particular work at hand whether single sheet or manifolding work and in a substantial range of adjustment. The adjustable stop provided for these purposes is also of advantage in facilitating the work of the operator by co-ordinating the key-stroke type impact, type rebound and letter-feed release of the carriage for various kinds of work and operating speeds.

As shown more clearly in Figures 1 and 2, the adjustable stop comprises a stop-bar 40 mounted for slidable motion relative to a cross-bar 41 on studs or screws 42 passing through inclined slots 78

43 in the stop-bar 40 and anchored in the cross-bar 41, the bar 41 extending across the machine and being supported on the main frame thereof. By the coaction of the inclined slots 43 with the 5 respective studs 42, lateral movement of the stop-bar 40 causes same to be raised or lowered so that its surface 44 is adjusted to or from a portion of each type-lever 14 adjacent its forward end to adjustably limit the down stroke thereof. 10 Each type-lever 14 has formed adjacent the forward end, a member or tongue 45 for engaging the bar 40. A screw 46 is journaled in the main frame of the machine and is secured against axial movement relative thereto as by a collar 15 47 and a knob 48. The screw 46 threadedly engages a lug 49 extending from the angle-bar 40. Rotation of screw 46 in either direction will raise or lower the bar 40 by coaction with the slots 43 and screws 42, to move its surface 44 toward or 20 away from the tongues 45 of the key-levers 14.

In the showing of the type-action in Figure 3, the stop-bar 40 has been lowered to afford a greater stroke for the key-lever and thus reduce the distance from the platen 32 at which the 25 type-bar begins to swing of its own momentum, such setting being preferred, for example, in manifolding wherein a greater type impact is desired.

Referring to Figure 4, the stop-bar 40 is shown 30 therein as being raised so as to limit the down stroke of the key-levers 14 so that the point at which the type-bar begins to travel of its own momentum is a greater distance from the platen such as would be required in single-sheet work. 35 It will be noted by joint reference to Figures 3 and 4 that by varying the extent of travel of the type-bar in its own momentum, the celerity of impact will also be varied at will of the operator to suit the type of work at hand, as well as for 40 other advantages set forth.

The movement of the type-bar in momentum, that is, when the key-lever 14 has engaged the stop-bar 40 and its down stroke is arrested, may be permitted, for example, by the inclusion of a 45 lost-motion device interposed at a suitable point in the type-action. However, in the present invention, the motion of the type-bar in momentum is permitted by the resilient yield of the component parts of the type-action, particularly the key-lever 14. In that the key-lever 14, at its fully 50 depressed position is supported at widely separated points, namely, on the pivot 16 at the rear end and at the forward end by the tongue 45 resting on the adjustable stop 40, a substantial 55 length of the key-lever 14 is in suspension and thus provides adequate resilience to flexing and acts substantially as a bow spring, as will be seen from the dotted-line showing of key-lever 14 in Figures 3 and 4. Since by adjusting the stop 40, the arc of the momentum stroke may be varied, 60 it will follow from this that the extent to which the key-lever 14 is flexed during the momentum stroke will accordingly be varied and therefore the celerity of impact of the type on the work 65 may be set to the desired degree.

In the reverse action, the flexed key-lever 14, during recovery to its normal state, augments the rebound or return of the type from the type-guide 35 to insure against the jamming of several 70 type-bars into the guide 35, as may result during high-speed typing. By adjustment of the stop-bar 40 the amplitude of the return action of the type-bar 28 may be set so as to obviate any chance of jamming the type at the guide 35, 75 at the same time assuring ample celerity of the

momentum stroke for either manifolding or single-sheet work.

As shown in Figure 5, the type-bars 28 are arranged to flex in whip action at the completion of the typing stroke, there being an anvil or stop-ring 57 on the type-bar segment 29 against which the intermediate portion of the type-bar strikes, at which instant same is caused to flex until its type-head strikes the work. The rebound of the type-bar 28 from its whip-action flexure co-operates with the flexed key-lever 14 in its recovery, both effecting the instant withdrawal of the type from the guide 35 after the type impression is made. 10

The tongues 45, extending from each of the 15 key-levers 14, provide for individual adjustment of each key-lever down stroke so as to co-ordinate the entire system of type-actions, particularly to vary the down-stroke of the type-keys in the outer type-actions with reference to the central group of type-actions to afford uniform type-impression throughout the machine. Accordingly, each tongue 45 depends from its key-lever 14 and projects forwardly in cantilever manner, the free end of the tongue 45 being disposed to engage 20 the surface 44 of the stop-bar 40. The tongue 45 is relatively rigid in structure but, being bendable, may be arranged to the desired setting to or 25 from its type-bar 14 so as to engage the stop-bar 40 with a lesser or greater down stroke of the key-lever 14 as required to co-ordinate same with the other type-actions. 30

A visual indicator is provided by which the operator may observe the setting of the adjustable stop 40, the indicator including a numbered 35 dial so that the operator may quickly adjust the stop to the desired key-stroke suitable for the work at hand, the dial indicating the celerity of impact of the type with the work for a certain setting of the stop-bar 40. A pointer 51 is 40 pivoted at 52 and has a member 53 thereof flexibly connected to the bar 40 by a fork 54 extending from the bar 40 to engage the member 53 so that as the bar 40 is adjusted, the indicating end 55 of the pointer 51 moves along the stationary 45 dial 56, the dial being calibrated or numbered as desired to designate the range of adjustment afforded by the stop-bar 40. 50

The escapement-mechanism, Figures 2 and 12, is similar to that usually employed in the Underwood typewriter and comprises a toothed escapement-wheel 58 co-operating with a pair of dogs 60, 61, mounted on a rocker 59. The feed dog 60 is pivoted on the rocker at 62 and is normally engaged by a tooth 63 of the escapement-wheel 58 so as to prevent rotation thereof, a spring 64, and the customary carriage-drive spring, not shown, functioning to hold the dog 60 in normal position in which it is stopped at abutment 65, Figure 12, on the dog-rocker 59. The spring 64 is so directed as to urge the rocker 59 to normal position against a stop 67 also urging the dog 60 normally against the abutment 65. The detent dog 61 is integral with the rocker 59 and has a bevelled face 66 which may engage the escapement-wheel tooth 63 when the latter is disengaged from the feed dog 60 by a rearward movement of the rocker 59. The escapement-wheel 58 carries a pinion 68 with which a gear rack 69 is in mesh, the latter forming a platen-carriage 70 rotatably supporting the platen 32. 65

The escapement-mechanism is actuated during swinging of each of the type-bars 28, same being provided with a shoulder 71 disposed to engage a universal bar 72 carried on a recipro- 70 75

cally mounted plate 73. As the type-bar 28 swings upwardly, the shoulder 71 engaging the universal bar 72, moves the plate 73 rearwardly against the tension of a spring 74 so that the 5 end of plate 73 engages the detent dog 61 to rock the rocker 59 in releasing the platen-carriage for letter-feeding.

Variations may be resorted to within the scope of the invention, and portions of the improvements may be used without others.

Having thus described my invention, I claim:

1. A type-action for typewriting machines comprising, in combination, a type-bar pivotally mounted to swing toward a platen in typing, a 15 pivotally mounted sub-lever including an arm disposed adjacent said type-bar, and means for transmitting the motion of said sub-lever to said type-bar for actuating same in typing and comprising a member slidably carried on said sub-lever arm for lateral movement relative thereto and engaging said type-bar, whereby to accommodate deviations in the respective paths of travel of the type-bar and sub-lever.

2. A type-action for typewriting machines comprising, in combination, a type-bar pivotally mounted to swing in an inclined plane toward a platen in typing, a sub-lever pivotally mounted to operate in a substantially vertical plane and including an arm terminating adjacent said 30 type-bar, and means for transmitting the motion of said sub-lever to said type-bar to actuate same in typing and comprising a member slidably carried on said sub-lever arm for lateral movement relative thereto and engaging said type-bar, whereby to accommodate deviations in the respective paths of travel of the type-bar and sub-lever.

3. A type-action for typewriting machines comprising, in combination, a type-bar pivotally mounted to swing in an inclined plane toward a platen in typing, a sub-lever pivotally mounted to operate in a substantially vertical plane and including an arm terminating adjacent said type-bar, and means for transmitting the motion of said sub-lever to said type-bar to actuate same in typing and comprising a roller rotatably carried on said sub-lever arm and having sidewise play relative thereto and engaging said type-bar, whereby to accommodate deviations in the respective paths of travel of the associated type-bar and sub-lever.

4. A type-action for typewriting machines comprising, in combination, a type-bar pivotally mounted to swing in an inclined plane toward a platen in typing, a sub-lever pivotally mounted to operate in a substantially vertical plane and including an arm terminating adjacent said type-bar, and means for transmitting the motion of said sub-lever to said type-bar to actuate same in typing and comprising a roller including side flanges defining a groove therebetween rotatably mounted on said sub-lever arm and having sidewise play relative thereto, said roller engaging an edge of said type-bar so that the flanges of the roller straddle the type-bar edge to maintain alignment of the roller with the type-bar, whereby to accommodate deviations of travel of the associated type-bar and sub-lever.

5. A type-action for typewriting machines comprising, in combination, a type-bar pivotally mounted to swing in an inclined plane toward a platen in typing, a sub-lever pivotally mounted to operate in a substantially vertical plane and including an arm terminating adjacent said

type-bar, and means for transmitting the motion of said sub-lever to said type-bar to actuate same in typing and comprising a stud projecting laterally from said sub-lever arm, and a roller rotatably carried on said stud for sidewise movement relative to said sub-lever arm and engaging parallel edges defining a slot in said type-bar, whereby to accommodate deviations in the respective paths of travel of the associated type-bar and sub-lever.

6. In a typewriting machine, a plurality of type-actions comprising, in combination, a series of type-bars, a type-bar segment presenting an arcuate pivot for said type-bars, the respective type-bars being guided for pivotal movement in planes of increasing inclination from the center to the outside type-action, a series of sub-levers pivotally mounted to operate in substantially vertical planes and including arms disposed adjacent the respective type-bars, means operatively connecting each of said type-bars and a corresponding sub-lever arm and comprising a stud projecting laterally from said sub-lever arm, a roller rotatably carried on said stud and having sidewise play thereon, and a slot in said type-bar for action of said roller therein, the sidewise play of said roller accommodating deviations in the respective paths of travel of the type-bar and sub-lever arm.

7. In a typewriting machine, a plurality of type-actions comprising, in combination, a series of type-bars, a type-bar segment presenting an arcuate pivot for said type-bars, the respective type-bars being guided for pivotal movement in planes of increasing inclination from the center to the outside type-action, a series of sub-levers pivotally mounted to operate in substantially vertical planes and including arms disposed adjacent the respective type-bars, means operatively connecting each of said type-bars and a corresponding sub-lever arm and comprising a stud projecting laterally from said sub-lever arm, a roller rotatably carried on said stud and having sidewise play thereon, and a slot in said type-bar for action of said roller therein, the sidewise play of said roller accommodating deviations in the respective paths of travel of the type-bar and sub-lever arm, said sub-lever arm studs being of varying lengths increasing from the intermediate type-actions to the outer type-actions.

8. A type-action for typewriting machines comprising, in combination, a first member having a portion operating in a straight path and a second member having a portion operating in an arcuate path adjacent the operating path of said first member, and means operatively connecting the said portions of said members and comprising a roller mounted for rotational and sidewise motion on one of said members and a slot in the other member, said roller engaging an edge of said slot for movement of said members in unison.

9. A type-action for typewriting machines, comprising, in combination, a pivotally mounted first member having a slot therein and a pivotally mounted second member including a roller rotatably carried thereon and having sidewise play relative thereto and engaging an edge of said slot, whereby to actuate one of said members by movement of the other member notwithstanding a deviation in the respective paths of travel of the first and second members.

WILLIAM F. HELMOND.
